TANDEM TRICYCLE

Lloyd G. Boursaw, Box 233, Rte. 2,
Rainier, Oreg. 97048

Filed Sept. 25, 1972, Ser. No. 291,986

Term of patent 14 years

Int. Cl. D12—11
U.S. Cl. D12—112

Fig. 1

Fig. 2

FIG. 1 is a right side elevational view of a tandem tricycle showing my new design, the left side being substantially a mirror image thereto; and

FIG. 2 is a top plan view thereof.

I claim:

The ornamental design for a tandem tricycle, as shown and described.
